UNITED STATES PATENT OFFICE.

ZACHARY TAYLOR JONES, OF NEW YORK, N. Y.

DESIGN FOR A HEAD OR FOOT BOARD.

SPECIFICATION forming part of Design No. 25,185, dated February 18, 1896.

Application filed December 16, 1895. Serial No. 572,369. Term of patent 7 years.

To all whom it may concern:

Be it known that I, ZACHARY TAYLOR JONES, a citizen of the United States, residing in the city of New York, county and State of New York, have invented and produced a new and original Design for a Head or Foot Board for Bedsteads, of which the following is a specification, reference being had to the accompanying drawing, which forms a part hereof.

The drawing represents in perspective a head or foot board for a bedstead which embodies my design.

My design for a head or foot board is composed of a broad rectangular surface *a*, defined at the ends by substantial posts *b b* and at the top by a horizontal bar *c*. The lines

of the posts *b b* are carried upward at the rear, as at *d d*, and at the top there is an overhang *e e*, upon which is a second horizontal bar *f*.
Short columns *g g* rest upon the lower portions of posts *b b* and appear to support the overhang *e e* and the bar *f*.
20

What I claim as my invention, and desire to secure by Letters Patent, is—
25

The design for a head or foot board for a bedstead, substantially as shown and described.

This specification signed and witnessed this 13th day of December, A. D. 1895.

ZACHARY TAYLOR JONES.

In presence of—

HENRY RAINY,
W. HARRIS SHEARER.
